UNITED STATES PATENT OFFICE.

HENRY C. SERGEANT, OF NEW YORK, N. Y.

ROCK-DRILL.

SPECIFICATION forming part of Letters Patent No. 326,681, dated September 22, 1885.

Application filed March 2, 1885. (No model.)

To all whom it may concern.

Be it known that I, HENRY C. SERGEANT, of the city and county of New York, in the State of New York, have invented a new and useful Improvement in Rock-Drills and other Engines, of which the following is a specification.

In carrying out my invention I employ a valve for controlling the admission of steam or compressed air to the drill-cylinder, which is like that shown in my application for Letters Patent No. 145,343, filed October 13, 1884; and I also employ mechanism for rotating the drill-piston and the drill or bit, which in some respects resembles that shown and described in my said application. In the drill to which I have reference, the cylinder is provided between its ends with an exhaust cavity or passage, which extends circumferentially around the cylinder, and across which the piston travels in its reciprocating movements. It will therefore be obvious that as soon as the piston in its downward or working stroke passes this exhaust cavity or port there is no longer any outlet for the exhaust, and hence it is possible that the compression of the vapor in the lower part of the cylinder might cushion the piston and reduce, to a certain extent, its striking force.

The object of one part of my invention is to prevent this; and to this end the invention consists in the combination, with a valve for controlling the admission of motive fluid to the cylinder, and an exhaust port or cavity intermediate between the ends of the cylinder, as described, of a supplementary exhaust-valve, which, when the pressure of motive fluid has acted upon the upper end of the piston to force it downward, will, by such pressure, be held open and allow the exhaust of any vapor which may be in the lower part of the cylinder through the port or passage which leads to the lower end of the cylinder and such supplementary exhaust-valve.

In my aforesaid application the mechanism for rotating the piston consists, essentially, of two rings having ratchet-shaped teeth on their faces, one ring being engaged with spiral grooves which are formed on the exterior of the piston-extension, and the other ring being held or clamped in place by force exerted by the buf-

fer-spring, which holds the upper head of the cylinder in place. The important advantage of this arrangement of parts is that the ring last mentioned is held in place or in fixed position solely by friction, and hence if the piston is difficult to turn in its upward stroke by reason of the bit catching in the hole, or from any other cause, both the ratchet-toothed rings will turn and prevent any breakage of parts.

Another feature of my present invention consists in the novel construction and combination of parts to enable these two rings having ratchet-teeth upon their engaging faces to be employed in connection with a spirally-grooved bar arranged concentric with the piston and fitting a nut secured in the piston.

The above-referred to features of my invention will be hereinafter described and pointed out in the claims.

In the accompanying drawings, Fig. 1 represents a longitudinal section of a portion of a drill embodying my invention. Fig. 2 represents a plan thereof. Fig. 3 represents a transverse section on the plane of the dotted line *x* *x*, Fig. 1. Fig. 4 is a horizontal section upon the plane of the dotted line *y* *y*, Fig. 1. Fig. 5 is a face view of one of the ratchet-toothed rings and the head of the spirally-grooved bar to which it is locked, and with which it is connected. Fig. 6 represents a face view of the other or accompanying ratchet-toothed ring, which is clamped and held in place by spring-pressure. Fig. 7 is an end view of the nut contained in the piston, and Fig. 8 is an end view of the main valve for admitting motive fluid to the cylinder.

Similar letters of reference designate corresponding parts in all the figures.

A designates the drill-cylinder, which, except in so far as hereinafter described, may be of ordinary construction.

B designates a piston fitted to reciprocate therein and having an attached piston-rod, B'. The piston B may be provided with any suitable spring-packing, as shown at *b*.

C designates the lower head of the cylinder through which the piston-rod B' works, and D designates the upper head thereof. This upper head, D, consists of a cylindric piece of metal fitting within the cylindric bore in the

ring D', which is secured by bolts *a* to the upper end of the cylinder. In this example of my invention, both the upper and lower heads are held in place by long bolts E, one 5 on each side of the cylinder. These bolts pass through and are provided with heads below the lower head, C, and pass through holes in the ring D', within which the upper head, D, is fitted.

10 F designates a spring, which, as here shown, consists of two steel plates placed one upon another and deflected or offset between their ends, so as to bear upon the cylinder-head D. The bolts E pass through the ends of these 15 spring-plates F and have applied to their ends nuts *e*. By tightening the nuts *e* it will be observed that the lower head will be held securely in place, and the springs F will be put under tension, and will thereby hold the 20 upper head, D, securely in place.

G H designate two rings, which form an essential part of the mechanism for rotating the drill-piston.

I designates the spirally-grooved bar, which 25 is concentric with the piston and cylinder, and has at the upper end a head, I', considerably larger in diameter than the bar.

In the cylinder A is formed a rabbet, *a'*, of considerable depth, and therein is fitted a scattering 30 ring, J, through which the spirally-grooved bar I projects, and against which the head I' of said bar bears, as shown in Fig. 1.

The rings G H are provided on their adjacent faces, which are in contact, with ratchet-teeth, which are shown in face view Figs. 35 5 and 6, and the inner ring, G, fits the internal rabbet *a'* in the cylinder, and is locked to the head I' of the spiral bar by lugs or ears *b'*, fitting diametrically opposite notches *b'* in 40 said head, as shown in Fig. 5; hence it will be seen that ring G and spiral bar I can only turn together and cannot turn independently of each other.

As is best shown in Fig. 1, the cylindric bore of the head-ring D' is slightly larger in diameter than the rabbet *a'* of the cylinder, and the ring H fits in this cylindric bore and bears against the end of the cylinder, said ring being supported in a rabbet, *c*, in the head D. It will therefore be seen that the springs F, by exerting their pressure upon the head D, clamp and hold the ring H by friction in its place between said head and the end of the cylinder. The spiral bar I is fitted to a nut, I², which may be made of brass or other metal adapted to work well with steel, and which is represented as screwed into the end of the piston-extension B², it being made a fixture therewith. The ring G has 55 a yielding support afforded by a spring, G', which is interposed between it and the ring J, as shown in Fig. 1. This spring G' may consist of a thin ring or annular piece of steel, which is deflected at diametrically-opposite 60 points in its circumference, which gives it a corrugated form and enables it to bear on both the rings J and G; hence it will be seen that

the ring G may be turned freely in one direction, the spring G' yielding to permit its ratchet-teeth to pass the ratchet-teeth of the 70 ring H.

From the above description it will be understood that when the drill-piston is forced downward to make its working-stroke, the nut I², acting upon the spiral bar I, turns said bar 75 and the ring G relatively to the ring H, the spring G' permitting the ring G to yield sufficiently for this purpose. On the contrary, however, when the piston performs its upstroke the spiral bar and the ring G are held against turning by the ratchet-teeth of rings G and H, and consequently the piston will be turned by the engagement of its nut I² with the bar I. If, however, when the drill makes its upstroke there should be any unusual resistance opposed to the turning of the piston, the ring H, being held by friction only, will turn and thus avoid any breakage of parts. By this construction I am enabled to employ the two ratchet-toothed rings, one of which is clamped and 85 held in its place by spring-pressure in connection with the central spiral bar and nut, which are now considered the most desirable means for rotating the piston, as by them no side wear is produced upon the cylinder or piston. 95

I will now proceed to describe the valve and ports or passages whereby the admission of motive fluid to the cylinder is controlled. In the cylinder A is formed a valve-chest, A', wherein is fitted a cylindric valve-casing A². 100 This casing rests upon the shoulder *a'*, formed in the chest A', and beyond it is placed a head, A³, and beyond the head is a plug, A⁴, whereby all are securely fixed in the chest. The valve K consists of a cylindric structure 105 having heads or disks *f*, in the peripheries of which are notches or holes, as shown in Fig. 8, and which is adapted to close on either of the valve-seats *g g'*. From the seat *g* a port or passage, *g**, leads to the lower end of the 110 cylinder, and from the seat *g'* a port or passage, *g'**, leads to the cylinder above the piston, and communicates with a belt for the passage of the motive fluid around the piston. The valve-casing A² is provided around its circumference with series of holes or openings *h*, through which the motive fluid may be passed from the belt *h*, which surrounds the valve-chest A', and with which communicates a supply-pipe, *h'*. Between the ports or passages 115 *g** *g'** the cylinder is constructed with a circumferential exhaust passage or belt, *i*, having at the top an exhaust-pipe, *i'*.

The valve and its mode of operation are similar to that shown and described in my 125 aforesaid application, and no special reference thereto is necessary. When the valve is in the position shown in Fig. 1, the seat *g* is open, and motive fluid can pass to the cylinder above the piston, and when the seat *g* is 130 open, motive fluid can pass through the passage *g** below the piston.

It will be understood that when the parts are in the position shown in Fig. 1 the motive

fluid is admitted through the passage g^* , and there is a free outlet for the exhaust below the piston through the exhaust-passage i ; but as soon as the piston in its downward movement passes the exhaust-passage i , exhaust through said passage will be prevented.

To obviate any cushioning of the drill-piston in its downward movement, I have arranged adjacent to the exhaust-passage i , and as shown in Figs. 1, 3, 4, a supplementary exhaust-valve, L , which I will now describe. This valve L is fitted to a cylindric bore, j , which extends in a horizontal direction into the side of the drill, and is closed by a plug, a^* , as is best shown in Fig. 4. The head of this valve is adapted to seat upon a shoulder, j' , and below its head the valve is of skeleton or ribbed construction, so that when open communication will be afforded between the exhaust-cavity i and the small chest j^2 of the valve L , through a port or aperture, i^2 , and through the cylindric bore j to which the valve is fitted. From the supply-belt g^* a port or passage, j^3 , leads to the inner end of the cylindric bore j , and from the small valve-chest j^2 a port or passage, j^4 , leads upward to the port g^* , which connects the valve-seat g with the lower end of the cylinder. The port or passage j^3 is shown by dotted lines in Figs. 1, 30, and the port or passage j^4 is shown clearly in Fig. 3.

Referring now to the operation of the machine, when the parts are in the position shown in Fig. 1 motive fluid passes through the seat g' and port or passage g^* to the cylinder, and passing upward around the piston-extension B^2 , acts upon the upper end of the piston and forces it downward. So long as the exhaust port or belt i remains open the motive fluid can exhaust freely through the same below the piston; but as soon as the piston covers the port i , that source of escape is closed. When the motive fluid passes to the upper side of the piston its full pressure passes through the passage or port j^3 , and acting against the inner end of the valve L throws the latter open; hence after the piston has covered the exhaust port or belt i any vapor which may remain in the cylinder below the piston can still pass through the ports and passages $g^* j^4$ into the chest j^2 , and thence, the valve L being open, can pass freely through the port or opening i^2 into the main exhaust-cavity i . When the valve K changes and steam is admitted through the seat g and port or passage g^* the full pressure instantly passes through the port j^4 to the chest j^2 , and acting on the head of the valve L closes it on the seat j' and prevents escape of the live motive agent through the port or opening i^2 into the exhaust-cavity i .

In order to facilitate the passage of steam to the upper end of the piston when the latter is making its downward stroke, I have formed in the piston-extension B^2 two, three, or more grooves, l , which extend lengthwise thereof, and which, as soon as they are brought

over the supply-belt g^* by the movement of the piston, serve as passages for the live motive fluid upward to act on the end of the piston-extension. At the lower end of these grooves or channels l , I have formed holes l' leading inward to the cavity or chamber B^3 in the piston which receives the spiral bar I , and through these holes the live motive fluid may pass to the cavity B^3 to act upon the bottom thereof, and so cause the live motive fluid to exert its force upon the whole area of the piston.

It will be obvious that, although I have only described my improved supplementary valve as applied to the rock-drill, it may be embodied in chipping-machines, riveting-machines, hammers, and other engines wherein are employed a cylinder and a reciprocating piston which operates a tool by percussion. The ring H forms a pawl which is held by friction in the cylinder and with which the ring G engages. The ring H might be dispensed with, and the ring G be made to engage with teeth or projections on the inner side of the head D ; but I consider the ring H preferable.

What I claim as my invention, and desire to secure by Letters Patent, is—

1. The combination, with a cylinder constructed with supply-passages for motive fluid, and the exhaust-passage intermediate between the supply-passages, of a reciprocating piston fitted to the cylinder and serving to close the exhaust-passage by its movement over the same, a fluid-actuated main valve which is operated automatically, substantially as herein described, to control the supply of motive fluid to the cylinder above and below the piston, and a supplementary exhaust-valve and ports, whereby the supply-passage leading to the lower end of the cylinder may be placed in communication with the main exhaust when the piston is on its downstroke to permit the exhaust of vapor from the lower end of the cylinder after the main exhaust-passage has been closed by the piston, substantially as and for the purpose herein described.

2. The combination, with a cylinder constructed with supply-passages $g^* g^*$, and the main exhaust-passage i , and also having a cylindric bore, j , and passages $j^3 j^4 i^2$, of a piston, B , the valve-seats $g g'$ and the valve K , and the supplementary exhaust-valve L , all arranged to operate substantially as and for the purpose herein described.

3. In a rock-drill, the combination, with a cylinder and piston and a spiral bar, of a ring having ratchet-shaped teeth upon its face, and locked to the head of the spiral bar, so as to slide lengthwise of the bar, and a spring forming a yielding support for said ring, substantially as herein described.

4. In a rock-drill, the combination, with a cylinder and piston, of a spiral bar fitting a nut in the piston, and two rings having ratchet-shaped teeth on their adjacent faces, one of said rings being supported by a spring and

locked to turn with the spiral bar, and the other ring being clamped and held by friction in the cylinder, substantially as herein described.

- 5 5. The combination, with a cylinder and reciprocating piston, of the upper head held in place by spring-pressure, a spirally grooved bar fitting a corresponding nut in the piston, and two rings having ratchet-shaped teeth upon their faces, one of said rings being clamped and held in place by spring pressure between the upper head and the end of the cylinder, and the other ring being locked to said bar, substantially as herein described.
- 15 6. The combination, with a cylinder, A, and a piston and piston-extension, B B², of the ring J, fitting a rabbet in the cylinder, the spirally-grooved bar I, fitting a nut in the piston extension, the rings G H, having ratchet-teeth upon their faces, and the former of which is

locked to the head of said spiral bar, the spring G', supporting the ring G, and the head D, with the springs F, for exerting a pressure thereon and by which the ring H is clamped in place, substantially as herein described.

7. The combination, with a cylinder and its supply-belt g*, of the piston B and piston-extension B², the spiral bar I, and ratchet-toothed rings for holding it, substantially as herein described, and the nut I², fitting said spiral bar, the piston-extension being provided with grooves and passages l l', whereby motive fluid will be conducted to the upper end of the cylinder and to the chamber in the piston which receives the spiral bar, substantially as herein described.

HENRY C. SERGEANT.
